(57) **CLAIM**

The ornamental design for a dual bag that includes a transparent inner bag and a black outer bag, as shown and described.

DESCRIPTION

FIG. 1 is a front view of a bag that includes a transparent inner bag and a black outer bag, the back view being the same as the front view; and,

FIG. 2 is an exploded view of the bag of FIG. 1 showing the transparent inner bag and the black outer bag.

The broken lines in the drawings illustrate portions of the dual bag that form no part of the claimed design.
